UNITED STATES PATENT OFFICE.

ALBERT B. DICK, OF CHICAGO, ILLINOIS.

PROCESS OF DUPLICATING TYPE-WRITTEN WORK.

SPECIFICATION forming part of Letters Patent No. 466,557, dated January 5, 1892.

Application filed October 20, 1890. Serial No. 368,705. (No model.)

To all whom it may concern:

Be it known that I, ALBERT B. DICK, a citizen of the United States, residing at Chicago, Cook county, Illinois, have invented a certain new and useful Improved Process of and Materials for Duplicating Type-Writer Work, of which the following is a specification.

My object is to enable the production upon any ordinary type-writing machine of a stencil from which a large number of copies can be printed, which copies will accurately resemble ordinary type-written matter.

Heretofore it has been proposed to provide the type with perforating-points which would form small holes in the stencil-sheet, representing the outlines of the types; but this method of preparing a type-writer stencil would require a special construction of type-writer not adapted for ordinary type-writing, and the stencil produced by such method would not give a copy resembling original type-writing. I have found that by the employment of a sheet of thin and porous paper, such as Japanese paper of that kind known as "dental paper" or "yoshino," coated with a substance impervious to ink, such as paraffine, and a covering-sheet on either or on each side of said coated sheet, preferably of a fine mesh fabric, the striking of the type causes the coating to be forced into or received into or onto the covering-sheet, or where a covering-sheet is employed on each side of the coated sheet, a portion of the coating is driven onto or into each of the covering-sheets, so that when the covering sheet or sheets are removed from the coated sheet the coating will be removed with it or them on the lines of the type, and the coated sheet is then a stencil-sheet with the fibers of its paper left exposed and unbroken where struck by the type. This stencil so produced can then be used to print duplicates from in the manner well understood, its surface being ink-proof, so that ink will not pass through to effect printing except where struck by the type.

The present invention relates to a process of forming the stencil wherein a covering-sheet is used on each side of the stencil-sheet during the operation of forming a stencil, whereby the ink-proof coating is partially removed by each covering-sheet on the lines

struck by the type. The process wherein but a single covering-sheet is employed on either side of the stencil is claimed in an application, Serial No. 252,003, filed by me October 11, 1887. The sheet to be used as the stencil-plate is made of thin paraffine or other suitably-waxed paper, which can be of any desired dimensions suitable for running through an ordinary type-writer. Preferably the paper employed as the retaining-body of the stencil-sheet is a Japanese paper of the kind known as "dental paper" or "yoshino," though any other material of suitable strength, thinness, and porosity may be used. The coating to be employed thereon is one which is soft enough to permit of its being driven into or onto the covering sheet or sheets and being removed from the stencil-sheet thereon. The covering-sheet employed by me is preferably a fine sheet of thin fine fabric, such as silk, bolting-cloth, or other suitable material having preferably a fine mesh. A sheet of tissue-paper of any open porous structure presents a surface having a fine mesh and may be employed successfully as a covering-sheet, whereon a portion of the ink-proof coating may be removed from the stencil-sheet. Preferably when tissue-paper is employed as a covering-sheet I employ it in front of the stencil-plate, as it will receive the face of the type and prevent any ink therefrom from being transferred to the stencil-paper, and can after one use be thrown away. With a sheet of tissue-paper employed as the front covering of the stencil-plate I prefer to employ as the back covering, so far as the process herein recited is concerned, a sheet of paper or other material that will present a firm and solid backing for the stencil-plate and front covering-sheet. These three sheets—to wit, the stencil-plate, front covering, and backing or back covering, the coverings both being of a nature to receive the coating of the stencil-plate and all being of a size to be run through a type-writer—are introduced therewith, the ink-ribbon being first removed and the machine operated in the ordinary manner, when it will be found that the face of the type will be produced on the stencil-plate without removing the coating therefrom, except to the extent of the type-surface, by rea-

son of the action of the covering-sheets, by which the coating is removed only where the type strike, leaving on the stencil-paper an exact reproduction of the type-face, as before described. An examination of the covering-sheets will show that a portion of the coating of the stencil-plate has adhered to and been carried off by each of them, the larger portion of the coating probably being found on the back covering-sheet.

The stencil-plate prepared as above stated, by the use of a covering-sheet on each side thereof, can be laid over a sheet of letter or other paper and an inking-roller run thereon, transferring to the letter or other paper the matter on the stencil-plate, and it will be seen that the matter thus reproduced will be in form and arrangement a duplicate of the work produced by the type-writer in all respects as to the character of the letters and the lines of printing.

In the accompanying drawing, forming a part of this specification, the single figure represents the stencil-sheet and its coverings in the form used by me as contemplated by this application.

A is the stencil-sheet, which, as before stated, is preferably of Japanese dental paper or yoshino coated with a soft paraffine or other suitable ink-proof coating material. B is the back covering-sheet, and C is the front covering-sheet. The three sheets A, B, and C being of a size to run through a type-writer are introduced therein, the ink-ribbon

being first removed and the machine operated in the ordinary manner, when it will be found that the face of the type will be produced on the stencil-plate without removing the coating therefrom, except to the extent of the type-surface, by reason of the action of the covering-sheets, by which the coating is removed only where the type strikes, leaving on the stencil-paper the exact reproduction of the type-face, as before described.

I claim—

The process of preparing a stencil for duplicating copies, consisting in introducing into a type-writing machine a sheet of porous material coated with an ink-proof substance, a sheet of paper arranged in the rear thereof, and a sheet of tissue-paper arranged in front thereof, to both of which paper sheets the ink-proof substance will adhere, then impressing the superimposed sheets with the matter to be copied, thereby causing the ink-proof substance of the coated sheet to adhere to the surface of the other sheets on the lines of impression, and then separating the sheets, thereby removing the coating from the ink-proof sheet on the lines of the type-impression, substantially as set forth.

This specification signed and witnessed this 18th day of October, 1890.

ALBERT B. DICK.
